GRINDING WHEEL FEEDING MECHANISM

Filed Feb. 12, 1942

FIG. 1

UNITED STATES PATENT OFFICE

2,349,786

GRINDING WHEEL FEEDING MECHANISM

Carl G. Flygare and Walter F. Johnson,
Worcester, Mass., assignors to Norton Company,
Worcester, Mass., a corporation of Massachusetts

Application February 12, 1942, Serial No. 430,664

5 Claims. (Cl. 51—95)

The invention relates to grinding machines, and more particularly to a control mechanism for an hydraulically operated grinding wheel feeding mechanism.

One object of the invention is to provide a simple and thoroughly practical hydraulically operated grinding wheel feeding mechanism for a grinding machine. Another object of the invention is to provide a wheel feed controlling mechanism which is arranged so that the grinding wheel may be fed rapidly as it is moved into operative engagement with the work, then at an initial grinding speed, after which the infeed is reduced to a very fine infeed.

A further object of the invention is to provide a wheel feeding mechanism with a normal grinding infeed which is automatically changed when the wheel reaches a predetermined position, to a fine infeed, after which a positive stop positively prevents further infeeding movement of the wheel. Another object of the invention is to provide a dash pot wheel feed controlling mechanism with a pair of control valves, both of which serve to control the initial grinding feed, after which one of the valves is cut off and the second valve controls a very fine infeeding movement of the grinding wheel.

Another object of the invention is to provide a dash pot feed control mechanism with two control valves, one for regulating the initial grinding feed and the other for regulating the final infeeding movement of the wheel combined with an electrically controlled valve which is closed when the second feed control valve is rendered operative to prevent leakage of fluid from the dash pot controlling mechanism through the first named valve. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of this invention,

Fig. 1 is an end elevation of a grinding machine embodying the invention, having parts broken away and shown in section, combined with a hydraulic piping and wiring diagram.

A grinding machine has been illustrated in the drawing comprising a base 10 which supports a transversely movable wheel slide 11 which is mounted on transversely extending ways (not 55

shown) on the base 10. The wheel slide 11 supports a rotatable grinding wheel 12 which is mounted on the end of a rotatable wheel spindle 13. The wheel spindle 13 may be driven by any of the well known mechanisms, such as an overhead belt drive or an electric motor 16 mounted on the wheel slide. As illustrated, a wheel driving pulley 14 is mounted on the opposite end of the wheel spindle 13 and is connected by a driving belt 15 with a pulley on the electric motor 16.

The base 10 also supports a longitudinally movable work table 17 which is arranged to reciprocate longitudinally relative to the base 10 on a flat way 18 and a V-way 19. The table 17 is provided with a rotatable work support including a headstock 20 and a footstock (not shown) each of which is provided with work supporting centers rotatably to support a work piece 21 in operative relation with the grinding wheel 12. The table 17 may be traversed longitudinally by a manually operable traverse mechanism which includes a rack bar 25 depending from the under side of the table 17. The rack bar 25 meshes with a gear 26 mounted on the inner end of a rotatable shaft 27. A manually operable traverse wheel 28 is mounted on the outer end of the shaft 27 and is arranged to be manually rotated to traverse the table 17 longitudinally relative to the base 10. If desired, a power operated table traversing or reciprocating mechanism may be provided, such as for example a mechanism of the type shown in the expired United States patent to Norton No. 762,838 dated June 14, 1904.

35 A wheel feeding mechanism is provided for manually feeding the grinding wheel toward and from the work, which comprises a half nut 35 depending from the wheel slide 11. The half nut 35 meshes with or engages a rotatable cross feed 40 screw 36. A forwardly extending portion 37 of the cross feed screw 36 is slidably keyed to a rotatable sleeve 38. The rotatable sleeve 38 is formed as an integral part of a rotatable shaft which is mounted in bearings 39 and 40 in the base 10. A manually operable feed wheel 41 is mounted on the outer end of a stud 42. The stud 42 carries a pinion 43 which meshes with a gear 44 mounted on the outer end of a sleeve shaft 38 so that a manual rotation of the feed wheel 41 serves to rotate the feed screw 36 in either direction to cause a forward or rearward feeding movement of the grinding wheel 12 and the wheel slide 11. The wheel feed 41 may be provided with a micrometer adjusting mechanism 45 which is substantially identical with that

shown in the above-mentioned prior United States patent to Norton. This micrometer mechanism serves precisely to adjust a stop abutment relative to the manually operable infeed wheel to compensate for wheel wear.

In the preferred construction the wheel slide 11 is arranged so that it may be moved toward and from the work piece 21 to grind the same to a predetermined size by means of a fluid pressure actuated wheel feeding mechanism. As illustrated in the drawing, the rear end of the feed screw 36 is rotatably supported in a slidably keyed bearing 50 which is supported in a casing 51 on the base of the machine. A fluid pressure cylinder 49 is attached to the casing 51 and contains a slidably mounted piston 52 which is connected by a piston rod 53 with the bearing 50 and is arranged so that when fluid under pressure is admitted to a cylinder chamber 54, the piston 52 will be moved toward the right into its rearward position, as illustrated in the drawing, transmitting a corresponding movement through the feed screw 36, the half nut 35, to move the wheel slide 11 and the grinding wheel 12 rearwardly to an inoperative position. Similarly, when fluid under pressure is admitted to the cylinder chamber 54 or the cylinder chamber 55, a rapid approaching or receding movement of the grinding wheel 12 and wheel slide 11 is provided.

A fluid pressure system is provided to supply fluid under pressure for moving the piston 52 so as to cause an infeeding or outfeeding movement of the grinding wheel 12. This system may comprise a reservoir 60 which is formed as a box-like section within the base 10 and serves to convey fluid through a pipe 61 to a fluid pressure pump 62. The pump 62 forces fluid under pressure through a pipe 63, to a control valve 64. The control valve 64 is preferably a piston type valve comprising a valve stem 65 having formed integrally therewith valve pistons 66, 67, 68 and 69. Fluid under pressure passing through the pipe 63 enters a valve chamber 70 located between the valve pistons 67 and 68 and passes through a passage 72, into the cylinder chamber 54, to move the piston 52 to its rearward position with the grinding wheel 12 separated from the work piece 21, as indicated in the drawing. During the rearward movement of the piston 52 toward the right, fluid is exhausted from the cylinder chamber 55, through a passage 76, into a valve chamber 77, between the valve pistons 66 and 67, and out through a pipe 78 which exhausts into the reservoir 60.

The valve stem 65 is arranged so that it may be moved endwise to shift the valve 64 into a reverse position so as to cause either a forward or rearward feeding movement of the grinding wheel 12. In the preferred construction a spring 80 is provided to maintain the valve 64 normally in its right-hand end position to cause the piston 52 and wheel slide 11 and grinding wheel 12 to remain in their rearmost position. A solenoid 81 mounted on the base 10 is provided to shift the valve 64 toward the left to cause a forward feeding movement of the grinding wheel 12 when desired. The solenoid 81 is connected by a link 82 with a stud 83 supported at the lower end of a rock arm 84. The rock arm 84 is pivotally supported by a stud 85 which is supported by a bracket 86 fastened to the base 10 of the machine. The upper end of the rock arm 84 is provided with a stud 87 which rides within an annular groove formed in a spool-shaped

member 88 supported on the left-hand end of the valve stem 65.

A suitable fluid pressure controlled or feed regulating mechanism is provided for modifying the rapid approaching movement caused by the piston 52 to obtain a controlled and predetermined infeeding movement of the grinding wheel 12. In the preferred construction a self-contained dash pot feed regulator is provided comprising a pair of dash pot cylinders 96 and 97 which contain dash pot pistons 98 and 99, respectively. The dash pot pistons 98 and 99 and their respective cylinders 96 and 97 are arranged with their axes parallel to each other and spaced on diametrically opposite sides of the piston rod 53. The dash pot pistons 98 and 99 are normally held in a rearward (right-hand) position by means of springs 100 and 101, respectively. An adjustable stop screw 102 serves to limit the rearward movement of the dash pot pistons 98 and 99, respectively. A slide sleeve 103 is supported on the rear extension 53a of the piston rod 53. The sleeve 103 has a flanged portion 104 which is either formed integral therewith or fixedly secured thereto. The flange 104 is arranged to engage the right-hand end faces of the dash pot pistons 98 and 99, respectively. The stop screw 102 engages the flange 104 and thereby serves to limit the rearward movement of the dash pot pistons 98 and 99 toward the right.

The rapid forward feeding movement of the grinding wheel 12 and wheel slide 11 continues until the adjustable nuts 105 on a threaded portion 106 of the extension 53a of the piston rod 53 engages the right-hand end of the sleeve 103. Continued movement of the piston rod 53a moves the sleeve 103 and the flange 104 toward the left and continued movement serves to move the dash pot pistons 98 and 99 in a direction toward the left. When the flange 104 engages the ends of the dash pot pistons 98 and 99, respectively, the rapid approaching or feeding movement of the grinding wheel 12 toward the work piece 21, as produced by the piston 52, is reduced to a slower predetermined grinding feed due to the fact that fluid confined within the dash pot cylinders 96 and 97, respectively, which are interconnected, exhausts through a passage 107, a needle valve 108, through a pipe 109, into a reservoir 110. By adjusting the aperture of the needle valve 108, a desired and predetermined infeeding movement of the grinding wheel 12 may be obtained.

When fluid under pressure is admitted to the cylinder chamber 54 to cause a rearward movement of the piston 52, the sleeve 103 together with the flange 104, is moved rearwardly by means of the released compression of the springs 100 and 101 which returns the dash pot pistons 98 and 99, respectively, to their rearward positions and moves the flange 104 and its supporting sleeve 103 toward the right until the flange 104 engages the adjustable stop screw 102. During the rearward movement of the dash pot pistons 98 and 99, a suction is created within the dash pot cylinders 96 and 97, respectively, which serves to aid in drawing fluid from the reservoir 110, through a pipe 111, and a ball check valve 112, to fill the dash pot cylinder chambers 96 and 97 for the next infeeding movement of the grinding wheel 12. During the infeeding movement of the dash pot pistons 98 and 99, fluid within the dash pot cylinders 96 and 97 serves to hold the ball check valve 112 closed so that fluid within the dash pot cylinders 96 and 97 is forced out

through the passage 107 and the needle valve 108, into the reservoir 110, to control the rate of the infeeding movement, as desired. An adjustable throttle valve 117 is provided to facilitate the exhaust of fluid from the dash pot chambers 96 and 97 after the port or passage 107 is closed by the piston 98. If desired, the needle valve 108 may be utilized to attain a final or finish grinding operation which is terminated when a positive stop collar 113 engages a stop surface 114 formed on the end plate enclosing the dash pot cylinders 96 and 97.

In certain grinding operations it is desirable to feed the grinding wheel into the work to reduce it to approximate size, after which the feeding movement of the grinding wheel is further slowed down or reduced to an extremely fine feed just prior to positively stopping the infeed by engagement of the stop collar 113 with the stop surface 114. This may be accomplished by providing an adjustable throttle valve 117 which is arranged to control the exhaust of fluid from the dash pot cylinders 96 and 97 after the port or passage 107 is closed by the forward movement of the dash pot piston 98. It will be readily apparent from the foregoing disclosure that the valve 117 may be entirely closed, in which case the needle valve 108 will control the entire infeed of the grinding wheel or, when desired, the throttle valve 117 may be opened to the desired extent so that after the closing of the port or passage 107, the valve 117 will control exhaust of fluid from the dash pot cylinders 96 and 97, thus facilitating an extremely fine precise feeding movement of the grinding wheel 12.

During the very fine final infeed of the grinding wheel 12, it is desirable that no fluid leak through the port or passage 107 and the needle valve 108. It is, therefore, desirable to provide a shut-off valve 118 having a movable cone-shaped frusto-conically shaped valve member 119 which is normally held in engagement with a valve seat 120 by means of a spring 121. The valve 118 is arranged so that when it is closed, no fluid can pass through the port 107 and valve 108 and from pipe 109 into pipe 109a into reservoir 110. A solenoid 122 is of the pull type which is arranged when energized to open the valve 118, that is, move the valve parts into the position illustrated in the drawing against the compression of the spring 121. A normally closed limit switch 123 is provided for controlling the solenoid 122. During the rapid approach and the initial grinding feed, the switch 123 remains closed to energize the solenoid 122 and to hold the valve 118 open.

An adjustable stop screw 124 is carried by a bracket 125 which is fixedly mounted on the stop collar 113. The stop screw 124 is arranged to move in the path of an actuating plunger 126 of the limit switch 123. The screw 124 is preferably adjusted so that when the valve piston 98 closes the port 107, the screw 124 will engage the plunger 126 and open the switch 123, thus deenergizing the solenoid 122 so that the released compression of the spring 121 will close the valve 118 so that no fluid leaking by the dash pot pistons may escape through the port 107 and valve 108 and pipe 109 into the pipe 109a and reservoir 110. After the valve 118 closes, all fluid exhausting from the dash pot cylinders must pass through the adjustable valve 117 which may be set to provide an extremely fine final feeding movement of the grinding wheel which continues until the stop collar 113 engages the stop surface 114.

The forward feeding movement of the grinding wheel 12, as controlled by the dash pot pistons 98 and 99, respectively, continues until an adjustable stop collar 113 carried by the sleeve 103 engages a fixed stop surface 114 on the rear face of the dash pot cylinder head. A lock collar 115 serves to position the stop collar 113 and to lock the same in adjusted position.

A throttle valve 116 is located in the pipe line 10 78 and serves to control the exhaust of fluid from the cylinder 49 so as to regulate the speed of movement of the grinding wheel 12 and its supporting wheel slide 11 during the rapid approaching or positioning movement thereof.

15 The infeeding continues until the stop 113 engages the stop surface 114 and positively limits the infeeding movement of the grinding wheel 12. The grinding wheel 12 is then allowed to remain in grinding contact with the work piece 20 21 for a definite predetermined time interval, after which the control valve 64 is reversed again to move the grinding wheel 12 to its rearward or inoperative position. The latter is accomplished by providing an electrical control system including an electrical time delay relay 140. Power is provided for the electrical control system from a source of power, as indicated by the power lines 141. The time delay relay 140 is so connected as to regulate and control the shifting movement 25 of the main control or feed control valve 64 so as to control the entire infeeding movement of the grinding wheel 12, namely, to control the overall cycle including the rapid approaching movement of the grinding wheel 12, the slower grinding infeed of the wheel, and the dwell which occurs thereafter before the grinding wheel is removed to its rearward or inoperative position.

30 A pair of push button switches 127 and 128 are mounted on the front wall of the machine 40 base 10. The push buttons 127 and 128 are arranged to be actuated by a control lever 129 which is pivotally supported on a stud 130 which is fixedly supported on the base 10 of the machine. The button 127 when pushed is arranged to cause 45 a rearward feeding movement of the grinding wheel 12 and its supporting slide 11 and the push button 128 when actuated serves to start the grinding cycle. The control lever 129 is normally held in a central or inoperative position by means 50 of the spring-pressed plunger 131 on the lever 129 engaging a V-shaped notch 132 formed in the lever supporting bracket, as shown. The spring-pressed plunger 131 and the V-shaped notch 132 are so shaped and arranged that when the lever 55 129 is moved either in a counterclockwise direction to initiate an infeeding movement or in a clockwise direction to interrupt the grinding cycle, the lever will automatically be returned to its inoperative or central position by means of the spring-pressed plunger 131 acting upon the V-shaped notch 132 as soon as the operator releases his grasp on the lever 129.

60 The time delay relay 140 is one of the standard electrically operated adjustable time delay relays, such as that known as the "Microflex" instantaneous reset timer, manufactured by the Eagle Signal Corporation of Moline, Illinois. The Microflex timer is a synchronous motor operated time delay relay and consists of a clutch-operating mechanism and a motor and gear train assembly, with an electromagnetically operated clutch for coupling them together. It is entirely automatic in action and requires only the closing or opening of the timer control circuit to initiate a 65 70 75 cycle of operation. The cycle is initiated by

momentarily closing the switch 128 of the timer control circuit. When the time interval terminates, thereby breaking the circuit, the solenoid 81 is deenergized which releases the compression of the spring 80 to reverse the control valve 64 and cause a rearward movement of the wheel slide 11 and the grinding wheel 12. The timer automatically resets for the next grinding cycle. If for any reason it is desired to stop grinding during a grinding cycle, the lever 129 is moved in a clockwise direction (Fig. 1) instantaneously to open the push button switch 127 which opens a circuit to interrupt the time delay relay and cause the grinding wheel to move to a rearward position.

The time delay relay may be adjusted to control the entire approaching and infeeding movement of the grinding wheel, that is, the rapid approach, grinding feed and dwell. The relay 140 allows a certain time interval to elapse after the push button 128 is actuated to initiate the forward movement of the grinding wheel 12 and to control the dwell thereafter so as to grind the work piece 21 to the desired and predetermined size. The time delay relay 140 is so connected with the push buttons 127 and 128 and also with the solenoid 81 that when the lever 129 is rocked in a counterclockwise direction to start a grinding cycle, the push button switch 128 is actuated to start the time delay relay 140 functioning and at the same time energizes the solenoid 81 which serves to shift the control valve 64 toward the left against the compression of the spring 80 to admit fluid under pressure from the pipe 63 through the passage 78, into the cylinder chamber 55, to cause the grinding wheel 12 and its supporting slide 11 rapidly to approach the work piece 21 at a rate governed by the throttle valve 116 located in the exhaust pipe line 78. The rapid approaching movement of the grinding wheel 12 and its supporting slide 11 continues until the sleeve 103 and its flange 104 engage the dash pot pistons 98 and 99, respectively, after which the rapid approaching movement caused by the fluid pressure operated piston 52 is slowed down to a slow uniform grinding speed as controlled by the exhaust of fluid from the dash pot cylinders 96 and 97, respectively, through a needle valve 108, into the reservoir 110. The slow grinding infeed continues until the adjustable stop 113 engages the stop surface 114 which positively limits the grinding infeed and allows the grinding wheel 12 to remain in grinding contact with the work piece 21 to finish grind the work.

After a predetermined time interval has elapsed according to the adjustment of the time delay relay 140, the solenoid 81 is automatically deenergized, thereby releasing the compressed spring 80 which returns the control valve 64 into the position illustrated in the drawing so that fluid under pressure passing through the pipe 63 passes through a passage 72 into the cylinder chamber 54 to cause the wheel slide 11 and grinding wheel 12 to move rapidly to their rearward or inoperative position.

The push button 127 is provided so that if for any reason it is desirable to interrupt the grinding cycle and cause the grinding wheel 12 to move rearwardly without completing its cycle, the lever 129 may at any time during the grinding cycle be moved in a clockwise direction to operate the push button switch 127 which serves through the time delay relay 140 to deenergize the solenoid 81 and thus allow the released compression of the spring 80 to shift the valve 64 into

the position shown in the drawing so that the grinding wheel 12 will move rapidly to its rearmost inoperative position.

The operation of this wheel feeding mechanism will be readily apparent from the foregoing disclosure. Assuming the various valves and other parts to have been previously adjusted to the desired positions for producing a predetermined grinding cycle, the lever 129 is moved in a counterclockwise direction to actuate the push button switch 128 which serves to set the time delay relay 140 in operation and at the same time energizes the solenoid 81 to initiate a forward movement of the grinding wheel 12 and wheel slide 11. The approaching movement of the wheel continues first at a rapid rate as determined by the valve 116 and is thereafter slowed down to a grinding feed by means of the dash pot pistons 98 and 99 which continues until the collar 105 engages the sleeve 103 to render the dash pots operative to slow down the rapid approach to a grinding feed of the wheel toward the work piece 21. The needle valve 108 controls the initial grinding feed which continues until the dash pot piston closes the port 107. After the port 107 is closed, the valve 117 controls a fine or final grinding feed of the grinding wheel. When the port 107 closes, the screw 124 opens the limit switch 123 to deenergize the solenoid 122, and the released compression of the spring 121 closes the valve 118 to prevent leakage of fluid through the port 107 and the needle valve 108 during the final feed. The final feed continues until the stop collars 113 engage the stop surface 114 positively to prevent further infeeding movement of the grinding wheel. The wheel remains in grinding contact with the work piece, after which the time delay relay operates to deenergize the solenoid 81, thereby releasing the tension of the spring 80 which moves the control valve 64 toward the right to initiate a rearward feeding movement of the grinding wheel.

It will be readily apparent that the time delay relay 140 controls the duration of the approaching movement of the wheel and also the period of dwell which follows it. By adjusting the valves 116, 108 and 117, the approaching and grinding feed of the wheel may be independently adjusted, and by manipulation of the time delay relay the over-all cycle, that is, the approaching and grinding feeds plus the period of dwell, may also be adjusted so that the entire cycle is under a definite time control.

It may be desirable for certain grinding operations to cut out the automatic cycle control and control the forward and rearward feeding movements of the grinding wheel 12 manually. This may be accomplished by placing a snap switch 135 in the electrical circuit. If it is desired to operate the wheel 12 under the control of the manually operable lever 129, the snap switch 135 is opened, thus rendering the time relay inoperative. In this condition of the electrical circuit, movement of the lever 129 in a counterclockwise direction operates the push button 128 to energize the solenoid 81 to initiate a forward approaching movement of the grinding wheel 12. Similarly, when the lever 129 is moved in a clockwise direction to operate the push button switch 127, the circuit is broken, thereby deenergizing solenoid 81, which serves through the released compression of the spring

80 to shift the control valve 64 into its reverse position to cause the grinding wheel 12 and its supporting slide 11 to move to a rearward position.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

We claim:

1. In a grinding machine having a transversely movable slide, a rotatable grinding wheel, means including a piston and cylinder rapidly to move said slide and grinding wheel transversely in either direction to position the grinding wheel relative to a work piece to be ground, means operative after a rapid advancing movement of the grinding wheel to produce a slower initial grinding feed of the grinding wheel, a solenoid valve to reduce the rate of infeed, an electric switch to control said solenoid, and adjustable means which is adjustably supported relative to and movable with said piston and wheel slide for actuating said switch after a predetermined initial feed so as to produce a slower final or finishing feed of the grinding wheel.

2. In a grinding machine having a transversely movable wheel slide, a rotatable grinding wheel thereon, means including a piston and cylinder rapidly to move said slide and grinding wheel transversely, and a self-contained dash pot feed regulator associated therewith including a reservoir, the dash pot piston and cylinder, adjustable connections to render said dash pot piston operative after a predetermined advance of the grinding wheel to produce a predetermined grinding feed of the wheel, an adjustable valve connected between said dash pot cylinder and said reservoir to control the initial grinding feed, a solenoid valve between said dash pot cylinder and said reservoir, and electrically controlled means actuated by and in timed relation with the piston after a predetermined initial grinding feed to actuate said solenoid valve so that the first of said valves thereafter regulates the exhaust of fluid from the dash pot cylinder to produce a fine or final grinding feed of the grinding wheel.

3. In a grinding machine having a transversely movable wheel slide, a rotatable grinding wheel, means including a piston and cylinder rapidly to move said slide and grinding wheel transversely in either direction, and a self-contained dash pot regulator associated therewith including a reservoir, a dash pot piston and cylinder, adjustable connections to render said dash pot piston operative after a predetermined advance of the grinding wheel to produce a

grinding feed of the wheel, a pair of adjustable independent valves between said dash pot cylinder and said reservoir to control the exhaust of fluid from the dash pot cylinder, thereby to regulate the initial grinding feed, a solenoid valve between one of said valves and the reservoir, means including a limit switch to control said solenoid valve, and means actuated by and in timed relation with the dash pot piston to actuate said switch and thereby close the solenoid valve during the final grinding feed to prevent leakage of fluid from the dash pot cylinder from escaping through the first of said valves.

4. In a grinding machine having a transversely movable wheel slide, a rotatable grinding wheel, means including a piston and cylinder rapidly to move said slide and grinding wheel transversely in either direction, and a self-contained dash pot regulator associated therewith including a reservoir, a dash pot piston and cylinder, adjustable connections to render said dash pot piston operative after a predetermined advance of the grinding wheel to produce a grinding wheel feed of the wheel, a pair of adjustable independent valves between said dash pot cylinder and said reservoir to control the exhaust of fluid from the dash pot cylinder, thereby to regulate the initial grinding feed, a solenoid valve between one of said valves and the reservoir, a limit switch to energize said solenoid to hold said solenoid valve open during the initial grinding feed, and means actuated by and in timed relation with the dash pot piston to actuate said switch and thereby close the solenoid valve during the final grinding feed to prevent leakage of fluid from the dash pot cylinder from escaping through the first of said valves.

5. In a grinding machine having a transversely movable wheel slide, a rotatable grinding wheel, means including a piston and cylinder rapidly to move said slide and grinding wheel transversely in either direction, and a self-contained dash pot regulator associated therewith including a reservoir, a dash pot piston and cylinder, adjustable connections to render said dash pot piston operative after a predetermined advance of the grinding wheel to produce a grinding feed of the wheel, a pair of adjustable independent valves between said dash pot cylinder and said reservoir to control the exhaust of fluid from the dash pot cylinder, thereby to regulate the initial grinding feed, a solenoid valve between one of said valves and the reservoir, a normally closed limit switch to energize said solenoid to hold said solenoid valve open during the initial grinding feed, and means actuated by and in timed relation with the dash pot piston to actuate said switch and thereby close the solenoid valve during the final grinding feed to prevent leakage of fluid from the dash pot cylinder from escaping through the first of said valves.
